COMBINED BICYCLE FITTER AND EXERCISER

Albert V. Scalingi, Winchester, and Allen R. Williams,
Jr., Lynnfield, Mass., assignors to Raleigh Industries
Limited, Nottingham, England

Filed Jan. 31, 1972, Ser. No. 222,426

Term of patent 7 years

Int. Cl. D21—02

U.S. Cl. D34—5 K

FIG. 1

FIG. 2

FIG. 4

FIG. 3

FIG. 1 is a front perspective view of a combined bicycle fitter and exerciser showing our new design;

FIG. 2 is a top plan view thereof;

FIG. 3 is a rear elevational view thereof;

FIG. 4 is a front perspective view of another embodiment of our new design wherein the step-through portion has been eliminated.

We claim:

The ornamental design for a combined bicycle fitter and exerciser, as shown and described.
